UNITED STATES PATENT OFFICE.

EDWARD B. COBURN, OF WORCESTER, MASSACHUSETTS.

ROOFING MATERIAL AND METHOD OF APPLYING THE SAME.

1,100,955.

Specification of Letters Patent. Patented June 23, 1914.

Application filed August 21, 1911. Serial No. 845,090.

To all whom it may concern:

Be it known that I, EDWARD B. COBURN, a citizen of the United States, residing at Worcester, in the county of Worcester and 5 Commonwealth of Massachusetts, have invented a new and useful Improvement in Roofing Material and the Method of Applying the Same, of which the following is a specification, accompanied by drawings 10 forming a part of the same.

My improvement relates to any of the forms thereof in common use, usually consisting of thin strips of felt rendered waterproof by saturation with any of the agencies 15 commonly used, such as tar, asphalt or oil.

The improvement in the roofing material consists of stamping longitudinal parallel grooves and ridges thereon, partially covering its surface to be exposed with slate dust 20 or similar material and dividing it into pieces or shingles of convenient size, and has for its object to enable it to be easily folded and also to allow of an accurate alinement in laying the shingles.

The improvement in the method of applying the roofing material consists of laying 25 the shingles by nailing them to the roof in parallel longitudinal rows with broken joints, and folding the material in such a manner that the heads of the nails, which are preferably flattened, are protected from 30 the weather by two thicknesses of the material both on their upper and lower sides, so that the rusting of the nails common in ordinary methods of roofing is avoided.

An additional advantage is that the flexibility and the folding of the material allow of its expansion or contraction under the influence of moisture or heat.

A still further advantage is that by covering the portions of the shingles to be exposed with powdered slate, or similar material, the roof when shingled has the appearance of a slate roof without impairing the 45 flexibility of those portions which require to be bent in laying.

Referring to the drawings, Figure 1 is a view of a strip of roofing material before it is divided into shingles showing the 50 grooves and ridge. Fig. 2 is an end view of Fig. 1 on a larger scale. Fig. 3 is a vertical, sectional view of a portion of a pitch roof showing the method of applying the material. Fig. 4 is a plan view of a por-

tion of a roof showing the material applied 55 by my method.

Similar reference characters refer to similar parts in the different figures.

Referring to the drawings, the material is first prepared in a long strip 1 of a convenient width, for instance, sixteen inches, and on one of its sides parallel, longitudinal grooves 2 and 3 and a ridge 4 are stamped. The material is then covered on one side between the groove 3 and its edge 5 and over 65 the ridge 4 with powdered slate or similar material. The strip thus prepared is then cut transversely on the broken lines 6^a, forming rectangular pieces whose length equals the width of the strip 1, in the present instance sixteen inches, and of any desirable width, say ten inches, forming what I term "shingles". The method of applying these shingles according to my invention is as follows: Along the lower edge of the roof 7 75 I first lay a continuous strip 8 with the surface covered with slate dust uppermost, as shown in Fig. 3. The object of this is to avoid open joints in the first row of shingles which are applied as shown by the broken 80 lines 8^a, which are nailed to the roof 7 within the space between the grooves 2 and 3 by nails 9. The shingles 6 are then bent in the direction of the arrow 10, Fig. 3, on the line of the groove 2 over the nails 9. The body 85 of the shingle 6 is next bent on the groove 3 in the direction of the arrow 11, Fig. 3, which completes the laying of a single shingle 6. This operation is continued until an 90 entire row is laid. The next row of shingles is laid in the same manner and so as to break the joints of the preceding row as is common in shingling roofs, as shown in Fig. 95 4, and the alinement is accomplished by placing the groove 3 upon the ridge 4 of the first row of shingles. In this way the entire roof is covered and is made weather tight at the ridge by nailing over the ridge pole a strip of the material, saddleboards, or any of the ordinary means.

100 I claim,

1. A roof covering comprising overlapping strips of flexible material, the lower of two adjacent strips having on its upper face a transverse ridge, and the upper of said strips having on the face opposed to said lower strip a transverse groove overlying 105 said ridge, and attaching means passing

through each strip, the edge of said upper strip being folded over said attaching means, and the body portion of said strip being folded along said groove over said folded edge.

5 2. The method of applying a sheet of flexible roofing material, consisting in nailing the material to the roof near one edge of the sheet, folding said edge over the attaching 10 nails, and folding the body portion of the sheet over the folded edge.

15 3. The method of applying a flexible sheet of roofing material having parallel grooves or indentations near one of its edges, consisting in nailing the sheet to the roof between said grooves, folding the sheet on the line of the groove nearest its edge to cover the nails, and folding the sheet on the line of the second of said grooves.

20 4. The method of applying a flexible sheet

of roofing material having a pair of parallel grooves or indentations near one of its edges, and a ridge spaced from and parallel with the innermost of said grooves and upon the same side of the sheet, consisting in applying the sheet to the roof with the grooves undermost, nailing through the space between said grooves, folding the sheet on the line of its outermost groove to bring the edge of the sheet over the nails, folding the 25 sheet over the nails on the line of its innermost groove, thereby bringing its ridge uppermost, applying a similar superimposed sheet with its innermost groove on the ridge of the first sheet, and nailing and folding 30 said superimposed sheet as above described.

EDWARD B. COBURN.
